UNITED STATES PATENT OFFICE.

ERNEST M. SCHWARZ, OF PHILADELPHIA, PENNSYLVANIA.

WINDOW SCREEN.

Application filed April 23, 1925. Serial No. 25,185.

My invention relates to new and useful improvements in a window screen, and more particularly to that class of window screens wherein a metallic frame is used and metal strips are utilized in removably fastening the screen fabric on the frame.

The primary object of this invention is to so construct a unique metal frame and retaining strips, the latter coacting with flanges or ribs of the frame to clamp a screen fabric on said frame.

A further object of the invention is to produce an enlargement on one side of the frame flange or rib with which will coact a channel retaining strip having flanges of different widths and coacting with the enlargement on the frame rib to clamp the screen fabric therebetween, the edges of which are bent about the rib enlargement by the retaining strips to securely fasten said screen fabric in place, it being understood that the retaining strips are secured to the frame by suitable fastening devices, such as screws.

With these ends in view, this invention consists in the details of construction and combination of elements hereinafter set forth and then specifically designated by the claims.

In order that those skilled in the art to which this invention appertains, may understand how to make and use the same, I will describe its construction in detail, referring by numerals to the accompanying drawing forming a part of this application, in which:—

Fig. 1, is an elevation of a screen constructed in accordance with my invention.

Fig. 2, is an enlarged section at the line 2—2 of Fig. 1.

Fig. 3, is an enlarged fragmentary perspective view of one of the frame members and a coacting corner angle separated from each other to clearly illustrate the construction.

Fig. 4, is an enlarged fragmentary perspective view of one of the retaining strips.

In carrying out my invention as herein embodied, 10 represents the side frame members and 11 the end frame members all of which are of identical construction and fashioned from sheet metal to produce a hollow body portion 12, preferably of rectangular shape in cross section and from the inner side of said body portion projects a rib 13 produced by two thicknesses of the metal in contact.

One thickness of the metal is of greater length than the other and is bent over said other portion to form what I term the tongue 14 and in the region of this tongue 60 the two thicknesses of metal forming the rib are bent back in reverse position to form the enlargement 15 on one side of the rib and when thus positioned the tongue 14 will lie between the two double thicknesses of 65 metal.

The several frame members are held together by the corner angles 16 each of which has a pair of arms at right angles for insertion in the ends of the hollow bodies 11 70 of adjacent frame members and said angle irons may be secured to the frame members in any suitable manner, as by spot welding.

Over the opening formed by the frame is stretched a suitable screen fabric 17 so that 75 its several edges overlie the enlargements on the ribs of all the frame members where said edges will be clamped by the retaining strips 18 when the latter are fastened by suitable fastening devices 19, such as screws, 80 passing through holes 21 in the ribs and more particularly in the enlargements of said ribs and threaded into the holes 20 in the retaining strips 18. Each of the strips is formed from a section of metallic channel 85 and has flanges 22 along the opposite edges. Each retaining strip is of a size to fit the enlargement 15 of a rib, as plainly shown in Fig. 2, and because of the cross sectional shape of the retaining strip the edge of the 90 screen fabric clamped between it and the rib enlargement will be bent about said enlargement so as to securely hold the screen fabric in place.

From the foregoing it will be seen that 95 when it is necessary to replace the screen fabric the several retaining strips may be removed by withdrawing the fastening devices and a new piece of screen fabric placed on the frame and fastened by the replacement of said retaining strips.

Of course I do not wish to be limited to the exact details of construction as herein shown as these may be varied within the limits of the appended claims without departing from the spirit of my invention.

Having thus fully described my invention, what I claim as new and useful is:—

1. A window screen consisting of frame members produced from sheet metal and fashioned to provide a hollow body portion 110 of rectangular shape in cross section, a rib

of two thicknesses of said metal, one thickness terminating short of the other, the longer thickness being bent over to provide a tongue and said rib bent back upon itself 5 to produce an enlargement with said tongue between two double thicknesses of metal, said enlargement having holes therethrough, a screen fabric having its edges disposed across the enlargements of all of the frame 10 members, retaining strips of channel sections overlying the edges of the screen fabric in the region of the enlargements of the frame members, said retaining strips having holes therein and screws passing through 15 the holes in the enlargements for threaded engagement with the retaining strips where-

by the latter are removably held in place to clamp the screen fabric.

2. In a window screen, a frame member produced from a single strip of sheet metal 20 and fashioned to provide a hollow body portion; a rib of two thicknesses of said metal, thereby providing two panels in contact with each other, one of the panels terminating short of the other, and the longer 25 panel being bent over to provide a tongue, and said rib bent back upon itself to provide an enlargement with said tongue between two portions of the cooperating panels.

In testimony whereof, I have hereunto 30 affixed my signature.

ERNEST M. SCHWARZ.
